UNITED STATES PATENT OFFICE.

FRANCIS A. WALLACE, OF WAYNESBURG, PENNSYLVANIA.

KEYBOARD-OPERATING APPARATUS FOR MUSICAL INSTRUMENTS.

SPECIFICATION forming part of Letters Patent No. 579,201, dated March 23, 1897.

Application filed June 16, 1896. Serial No. 595,784. (No model.)

To all whom it may concern:

Be it known that I, FRANCIS A. WALLACE, a citizen of the United States, residing at Waynesburg, in the county of Greene and State of Pennsylvania, have invented a new and useful Keyboard-Operating Apparatus for Musical Instruments, of which the following is a specification.

My invention relates to a keyboard-operating apparatus for musical instruments, such as organs and pianos; and the object in view is to provide means for applying a yielding or cushioned pressure to the keys of an instrument, whereby the operation of the keys is similar to that produced by manual pressure; to provide means for varying the tension of the key-levers to suit resistance offered by the keys of the instrument; to provide means whereby the apparatus may be arranged in different positions with relation to the keyboard to vary the scale of the performance, and to provide simple and efficient means for operating the apparatus.

Further objects and advantages of this invention will appear in the following description, and the novel features thereof will be particularly pointed out in the appended claims.

In the drawings, Figure 1 is a perspective view of a keyboard-operating apparatus constructed in accordance with my invention applied to an organ. Fig. 2 is a plan view of the same. Fig. 3 is a section on the line 3 3 of Fig. 2 to show the means for communicating motion to the key-levers. Fig. 4 is a detail view in perspective of the means for communicating rotary motion to and shifting the cylinder. Fig. 5 is a detail view in perspective of one of the operating-levers detached. Fig. 6 is a similar view of one of the pressure-buttons and the contiguous portion of the key-lever.

Similar numerals of reference indicate corresponding parts in all the figures of the drawings.

The key-levers 1, which are adapted for depressing the keys of the instrument, are preferably fulcrumed in a frame 2 by means of a pivot-pin 3, and in order to economize space the inner members of the series may overlap, as indicated in Fig. 2. The rear or inner ends of the key-levers are connected by means of

draw-wires 4 with the superjacent extremities of intermediately-fulcrumed operating-levers 5, of which the extremities of the short arms 55 are arranged in the paths of the pins or projections on the cylinder 6. The operating-levers are preferably reduced to adapt them to yield when strained by the engagement of a pin or projection of the cylinder, and the 60 extremities of the key-levers, which are held elevated by the keys of the instrument, are pressed downwardly to counteract a portion of the resistance of the keys by means of tension-springs 7, connected to an adjusting 65 roller or drum 8, mounted parallel with the axis of the cylinder and held at the desired adjustment by means of a removable pin 9, adapted to be engaged with one of a plurality of sockets 10 in said roller or drum. 70

It is desired to adjust the tension of the springs to provide for the depression of the keys by a slight pressure upon the short arms of the operating-levers, and hence the necessity for employing resilient connections between the cylinder and the operating extremities of the key-levers; but in order to secure uniform pressure of the key-levers upon the keys even when the resistance offered by the keys is not uniform I employ pressure-cushions 11 on the free ends of the key-levers, provided with threaded stems 12, mounted in the key-levers and provided at their upper extremities with heads or thumb-wheels 13. This provision of adjustable pressure cushions or buttons enables me also to adjust the device to any desired position with relation to the keyboard of the instrument and suit the different elevations of the white and black keys at the given adjustment. For instance, the levers which are employed to depress the white keys at one adjustment of the apparatus may be arranged in operative relation with the black keys at another adjustment, and inasmuch as the black keys are elevated above the plane of the white keys it is necessary to change the adjustment of the pressure cushions or buttons to cause the desired pressure upon all of the keys. 95

The cylinder is mounted in a rocking frame 100 14, in which it is held by means of terminal spindles 15 and 16 to removably secure the cylinder in place, the spindle 15 being connected with operating devices, while the spin-

dle 16 is capable of longitudinal movement and is provided with an actuating-spring 17 to hold it normally in position for engagement with a socket in the end of the cylinder.

5 In the construction illustrated the means for communicating motion to the operating-spindle of the cylinder include a driven shaft 18, having a worm 19, which meshes with a worm-gear 20 on said spindle, and a pulley 21 or its equivalent secured to the driven shaft, the pulley being traversed by a belt 22. In order to provide for shifting the cylinder longitudinally at the end of each complete operation thereof, I employ a cam 23, pivotally mounted upon a fixed bracket 24 and having a slot 25, through which extends the spindle, said cam being held in its normal position by means of a spring 26. The operating-spindle is fed longitudinally by means of a feed-screw 27, meshing with a stationary feed member 28, and the cam is depressed to throw the rocking frame forward sufficiently to disengage the feed-screw from the stationary feed member by means of the engagement of a trip-arm 29 on the spindle with a lateral lug 30 on said cam when the cylinder reaches the limit of its movement in the direction in which it is moved by the feed-screw.

Any suitable means for communicating motion to the belt may be employed, such as a driving-shaft 31, mounted upon pendent brackets 32 and having a belt-pulley 33, said driving-shaft being provided with a hand-wheel 34. I have also shown in dotted lines 35 in Fig. 2 a belt connecting the pulley 21 with a driving-pulley 35 on a spindle 36, to which is adapted to be attached an operating-crank 37.

In the construction illustrated in the drawings the driving-shaft is provided with cranks 38, connected by pitmen 39 with the foot-treadles 40 of an organ. The means for securing the casing to the frame of the instrument consists of a clamp 41.

Various changes in the form, proportion, 45 and the minor details of construction may be resorted to without departing from the spirit or sacrificing any of the advantages of this invention.

Having described my invention, what I claim is—

50

1. In a device of the class described, the combination of key-levers adapted to bear upon instrument-keys and designed to be elevated to their normal positions by said keys, yielding means for depressing the key-levers 55 to neutralize a portion of the resistance of the keys, yielding or resilient operating-levers connected respectively with the key-levers, and means for actuating the operating-levers to depress the free ends of the key-levers, 60 substantially as specified.

2. In a device of the class described, the combination of key-levers adapted to bear upon instrument-keys and designed to be elevated to their normal positions by said keys, 65 yielding means for depressing the key-levers to neutralize a portion of the resistance of the keys, yielding or resilient operating-levers connected respectively with the key-levers, and an actuating-cylinder having pins or projections to engage the extremities of the operating-levers, whereby the extremities of the key-levers are forcibly depressed to actuate the keys, substantially as specified.

3. In a device of the class described, the 75 combination of key-levers adapted to bear upon instrument-keys and designed to be elevated to their normal positions by said keys, tension-springs for depressing the key-levers to neutralize a portion of the resistance of 80 the keys, a drum to which the tension-springs are attached, means for securing the drum at the desired adjustment, whereby the tension of the springs may be made proportionate to the resistance of the keys, and means for communicating motion to the operating-levers to depress the keys against the unneutralized portion of their resistance, substantially as specified.

In testimony that I claim the foregoing as 90 my own I have hereto affixed my signature in the presence of two witnesses.

FRANCIS A. WALLACE.
